UNITED STATES PATENT OFFICE

STEWART C. WHITMAN, OF NEW YORK, N. Y., ASSIGNOR OF ONE-HALF TO GEORGE SHACKELFORD, OF NEW YORK, N. Y.

METHOD FOR RECORDING SOUND EMPLOYING A SEPARATE SOURCE OF ELECTRICAL ENERGY

Application filed June 30, 1930. Serial No. 465,025.

My invention relates to a method of recording sounds photographically using a separate source of electrical energy. This separate source of electrical energy may be used for sound recording on photo-sensitized motion picture film and may be used in the production of phonograph sound records and the reproduction of sound records. It also may immediately be adopted in connection with the projection and reception of television when or wherever a separate source of electrical energy is required to relieve the amplifier from being used as a power supply.

In the art of recording on sensitized motion picture film, said separate source of electrical energy adds to the faithful reproduction of sound, covering the full band of musical frequencies in conjunction with the use of said separate source of electrical energy. I use a special type of container of my own invention for recording to handle the output of said separate source of electrical energy.

These special types and designs of recording containers are constructed to handle the output of said separate source of electrical energy. I have, in my experiments, used the enclosed type of container, which is made of glass, and in some cases, I have used a chamber or container made of bakelite, fiber, rubber and the like having one end closed and the other end open to allow the passage of air and light. I have also used these electrical light discharges in a compressed air container. When used in a compressed air container, I find that I get a more perfect blue light discharge which gives better results for the adaptation of photographic reproduction. Furthermore, I find that I get an almost perfect blue light discharge, but not as perfect a blue as I do using a compressed air container. When I use the open end chamber, I find in my experiments of machination, that using a light discharge in a compressed air container and also using it in an open end container where the air can get to it, the aforesaid light discharge has a more penetrating valuation for photographic reproduction. I have also used this said light discharge in a vacuum container with

very good results. I have tried several different kinds and mixtures of gases such as argon, helium and neon with fair results. There are many types of contacts and many methods that may be employed in connection with said light discharge, such as anodes and cathodes.

I have shown a few types of these containers in the accompanying drawings, which embody two adjustable half moon circular plates forming a slit or aperture contact therein, so that the electrical energy may discharge against it and pass said electrical light impulses through said slit or aperture causing a superfine light line to be transmitted by exposure to the photo-sensitized motion picture film.

Figure 1 is a schematic diagram representing the output of a sound amplifier having a separate source of electrical energy with its output.

Figure 2 represents another schematic diagram of another form of sound recording amplifier having a separate source of electrical energy with its output.

Figure 3 represents still another schematic diagram of a sound recording amplifier with a separate source of electrical energy with its output.

Figure 4 represents a sound amplifier and a separate source of electrical energy using a high tension spark coil showing its output making contact with a suitable slit, using the slit as one of the contacts, and a lens combination of a photo-sensitized motion picture film.

Figure 5 represents a sound amplifier and a separate source of electrical energy, using a high tension spark coil showing its output enclosed in a container, enclosing the electrical light discharge, through a cylindrical lens held against a photo-sensitized film by a spring and suitable slit.

Figure 6 is a partial sectional view of an electrical high frequency or high tension electrical discharge container enclosed.

Figure 7 is a partial sectional view of an electrical high frequency, or high tension electrical discharge container open at one end.

Figure 8 is a partial sectional view of an electrical high frequency, or high tension electrical discharge container enclosed with an electrical contact outside the enclosure.

5 Figure 9 is a partial sectional view of a high tension, or high frequency electrical discharge container showing the elements therein.

10 Figure 10 is still another partial sectional view of a further form of high tension or high frequency electrical discharge container showing the elements therein.

Figure 11 is a partial sectional view showing an open high tension spark gap.

15 Figure 12 is a similar view showing an enclosed high tension spark gap.

The same part is designated by the same reference characters wherever it occurs through the several views.

20 In order to record my method on a photo-sensitized motion picture film, the sound amplifier 1 receives on its input side modulated high frequency impulses and these sound impulses are passed from the output of

25 said sound amplifier 1 and are then passed to a separate source of electrical energy, as shown at 2 and while at this point the sound impulses are impressed on suitable coils, transformers, chokes, and the like as shown at

30 3. Various conventional forms of electrical hook-ups, circuits and means are shown in Figures 1, 2, 3, 4 and 5 in the accompanying drawings.

35 The impulses when impressed on the aforesaid separate source of electrical energy as disclosed in Figures 1 to 5, inclusive cause an electrical light discharge to take place at 6, as shown also in Figures 1 to 5, inclusive. This electrical light discharge is used to expose a photo-sensitized motion picture film on a suitable location on the film 7 shown in Figures 3, 4 and 5. When these sound impulses do not pass the source 2 there is no electrical light discharge at 6

40 and consequently there is no exposure on said photo-sensitized motion picture film 7. This is due to the separate source of electrical energy furnishing the power for the electrical light discharge from a separate source of

45 electrical energy as shown at 2 and there is no direct connection between the sound recording light 6 and the sound amplifier 1, there is no steady flow of audio-frequency electrical impulses and as the said separate source of electrical energy is a high frequency electrical energy, the said audio-frequency sound impulses are used only to control and modulate high frequency light discharges. Thus these light discharges are

50 used to expose a photo-sensitized motion picture film by which there is a motion picture of sound impulses photographed thereon.

In my co-pending application, Serial No. 465,024, and filed June 30, 1930, I show and

65 describe divers methods of photographing

sound on sensitized motion picture film using an electrical light discharge from a separate source of electrical energy having first, a sound track on either marginal edge; second, a sound track inside the sprocket holes 70 on a motion picture film and third, a sound track inside the sprocket holes on a motion picture film adjacent to a motion picture.

I also show in said co-pending application, a sound track covering the full width inside 75 the sprocket holes on a photo-sensitized motion picture film.

In Figure 4 of the drawings, I have shown the lamp 6 in association with an adjustable slit 8 and lens elements 9 arranged in order 80 forward of the film 7. In Figure 5 of the drawings, I have illustrated the lamp 6 in association with a lens element 9 held forward of a slit 8 just forward of the film 7. Various forms of lens elements and slits may 85 be used in carrying out my invention, both of the forms herein shown in Figures 4 and 5 being illustrated in my copending application, Serial No. 465,024.

In Figures 6 to 12, inclusive, I have shown 90 various lamp forms which may be used in the output of the separate source of energy. Any of these forms of lamps may be used. In Figure 6, I have shown an enclosed type, the bulb being designated by the numeral 10 95 and the electrode by the numeral 11.

In Figure 7, I have shown a lamp of the open type in which the bulb is designated by the numeral 12 and the electrode by the numeral 13. 100

In Figure 8, I have shown a further form in which the bulb has outside contacts. Here the bulb is designated by the numeral 14, the same being of the enclosed type having an inner electrode 15. An outer band is designated by the numeral 16 having the wire 17 leading thereto. 105

In Figure 9, a form is shown of the enclosed and open type in combination, the outer bulb being designated by the numeral 110 18. Within the bulb is an open shell 19 having the electrode 20 therein. Leading from the shell 19 are the two contacts 21 and 22.

In Figure 10, I have shown a still further modification of the enclosed type in which the bulb is designated by the numeral 23. Therewithin is an open shell 24 lined as shown at 25. A central electrode is designated by the numeral 26 and an outer electrode is designated by the numeral 27, the latter extending around and bent inwardly through the open end of the shell 24 and having contact with the inner lining 25 adjacent its outer end. 115

In Figure 11, I have shown a still further modification in which the shell is designated by the numeral 28 having an opening 29 in the front thereof. Electrodes 30 and 31 project inwardly from the sides of the shell 28, said electrodes respectively leading from 120 130

the wires 32 and 33 which are supported in the sides of the shell 28 through the medium of the bearings or the like 34.

In Figure 12, I have shown a still further modification in which the lamp bulb is of the enclosed type, said bulb being designated by the numeral 35. A pair of wires 36 and 37 extend longitudinally in the bulb and have their outer ends bent inwardly toward one another as shown at 38, the free ends of same being spaced to form the gap 39.

Various other modifications and changes in details and various changes in electrical hook-up and designs of containers and elements and various ways and means for electric light discharges will occur to those

skilled in the art without departing from the spirit and scope of my invention as defined in the claim.

Having thus described my invention, what I claim is:

An apparatus for producing a highly actinic light for recording purposes comprising a high frequency mechanical buzzer, inductively coupled means for stepping up the high frequency voltage impulses across the solenoid of the buzzer, a light discharge connected in series therewith and means for modulating the current in the buzzer circuit at audible frequencies.

In testimony whereof I affix my signature.

STEWART C. WHITMAN.
